(57) **CLAIM**

The ornamental design for a moisture barrier, as shown and described.

DESCRIPTION

FIG. 1 is a front perspective view of a moisture barrier;
FIG. 2 is a front view of the moisture barrier shown in FIG. 1;
FIG. 3 is a back view of the moisture barrier shown in FIG. 1;
FIG. 4 is a side view of the moisture barrier shown in FIG. 1 having a mirrored side not shown; and,
FIG. 5 is an end view of the moisture barrier shown in FIG. 1 having a mirrored end not shown.

For FIGS. 1–5, lines shown as broken are for illustrative purposes only, showing the environment, and form no part of the claimed design.
